PISTON ACTUATED SWITCH

Elmer F. Kettunen, Windsor, Ohio

Application July 11, 1935, Serial No. 30,867

4 Claims. (Cl. 200—82)

My invention relates, in general, to piston actuated switches, and more particularly to piston actuated switches that are adapted to control flasher or warning signal lights.

5 An object of my invention is the provision of a pressure actuated device, taken in combination with a toggle actuated switch having a quick acting arm, wherein there is means provided by the movement of the quick acting arm to control the pressure actuated device.

Another object of my invention is the provision of an alternately actuated switch that may be utilized to control a dual set of flasher or warning lights upon a motor vehicle.

15 A further object of my invention is to provide for decreasing the frequency at which the dual set of flasher lights are operated as the speed of the vehicle increases, and for increasing the frequency at which the dual set of flasher lights 20 are operated as the speed of the vehicle decreases, when the vehicle is running normally on a level road.

Another object of my invention is the provision of operating my piston actuating switch 25 by the vacuum developed in the intake manifold of an internal combustion engine.

Other objects and a fuller understanding of my invention may be had by referring to the following description and claims, taken in conjunction with the accompanying drawing in which;

Figure 1 represents a cross-sectional and longitudinal view of a piston actuated switch embodying the features of my invention;

Figure 2 represents a cross-sectional and transverse view of the piston actuated switch, taken along the line 2—2 of Figure 1;

Figure 3 represents a fragmentary and cross-sectional view of the valve for controlling the reciprocatory movements of the piston actuated 40 device; and

Figure 4 represents a perspective view of the toggle switch and valve assembly.

With reference to the drawing, my invention comprises two main parts; namely, the cylinder 45 and piston assembly which is designated generally by the reference character 10, and the toggle switch and valve assembly designated generally by the reference character 9. The cylinder and piston assembly will be described first.

50 As illustrated, the cylinder is constructed of a left hand, semi-cylinder 11 and a right hand, semi-cylinder 12 having their open ends circumferentially joined together, such as indicated by the reference character 19. These two semi-cylinders 11 and 12 are secured together by means

of a central clamp band 13. The end of this central clamp band 13 is provided with ears through which a screw 17 extends and engages the body of the bracket 15 which is mounted on top of the cylinder. Also there are screws 14 which extend through the central clamp band 13 and threadably engage the two semi-cylinders 11 and 12.

5 The piston comprises a right hand head 20 and a left hand head 21 connected together by a longitudinal member 22. The two piston heads 20 and 21 are of like construction and in their description the corresponding parts are designated by the same reference characters.

In order to provide a good air tight seal, there is provided a leather gasket 23 that is positioned between each of the piston heads and the cylinder. An end washer 24 is held against the end face of the leather gasket 23 by means of a screw 25. Each of the piston heads is provided with a circumferential groove in which is mounted a spring 26 that resiliently presses the leather gasket 23 against the inside surface wall of the cylinder. This construction provides a good air tight seal so as to obtain efficient operation of the cylinder and piston assemblies. As illustrated, 15

20 there is provided in each of the piston heads a concentric depression 28 which is filled with grease 27, so that as the piston is actuated and the grease heated, the said grease tends to flow between the inner face of the leather gasket 23 and the end of each of the piston heads. In this manner the leather gasket 23 is well lubricated 25

30 so as to preserve long life and wear. As illustrated, the piston is foreshortened and thus provides a left hand piston chamber 29 and a right hand piston chamber 30. The reciprocatory movement of the piston is controlled by the toggle switch and valve assembly indicated generally by the reference character 9 which will now be 35

described.

30 The cylinder and the bracket 15 which is mounted thereon are provided with an opening 18 along its upper edge through which the lowermost part of the toggle switch and the valve assembly 9 extends into the cylinder. Integrally connected to the body bracket 15 is an upright bracket 33 against which the cup-shaped valve 41 slides. As illustrated best in Figure 4, the

45 toggle switch and valve assembly 9 comprises in general a saddle 50, a swinging arm 49, an oscillatory offset lever 54, and a spring 53. The saddle 50 may be constructed of a metal stamping and

50 comprises two oppositely disposed sides 51 and 52 which extend into the cylinder. The lower 55

55

edges of the two sides 51 and 52 is provided with a small recess into which the shoulders 56 and 57 of the oscillatory offset lever 54 engage, thereby establishing a fulcrum for the oscillatory offset lever 54. The lower end of the oscillatory offset lever 54 is bent in the form of a loop 55 which fits into the socket 31 of the longitudinal member 22 that interconnects the two heads of the piston. The swinging arm 49 is provided at its lower end with two notches 66 and 67 which rest respectively upon two outwardly extended tabs 64 and 65 of the saddle 50. These tabs provide the fulcrum for the swinging arm 49. Extending across the sides of the swinging arm 49 is a pin 62 to which the upper end of the spring 48 is attached. The lower end of the spring 48 is hooked into an opening 63 provided in the upper end of the oscillatory offset lever 54. The entire unit as shown in Figure 4 is resiliently held together by the spring 58. Therefore, in mounting or dismounting the toggle switch and valve assembly 9, it may be inserted or removed as a unit. The swinging arm 49 may be constructed of a metal stamping in which the two upper switch tabs 72 and 73 may be formed during the stamping operation. Attached respectively to the two switch tabs 12 and 73 are switch contact points 75 and 74 which alternately engage two similarly constructed switch arms 76 that are mechanically connected to, but insulated from, the saddle 50 and the body bracket 15. The right hand contact arm 76 is provided with a lower horizontal portion that is held between the two blocks of insulation 78 and 79, by means of the screws 80, which screws also hold the saddle 50 to the upper side of the bracket 15. The lower end of the right hand contact arm 76 extends to the right of the insulating blocks 78 and 79 to form a terminal connection 84 which may be connected in circuit relation with a lamp of a dual flasher system. The left hand contact arm 76 is provided with a lower horizontal portion and is held between the two insulating blocks 81 and 82 by means of the screws 83 which screws also hold the saddle 50 against the upper part of the bracket 15. The lower left hand end of the contact arm 76 extends to the left of the two insulating blocks 81 and 83 and forms a terminal 85 which may be connected in circuit relation with a lamp of a dual flasher system. The common connection of the dual flasher system may be connected to the terminal 86 which is electrically connected to the swinging arm 49 through means of a body bracket 15 and the saddle 50.

As illustrated, the rearward side of the swinging arm 49 is provided with an opening 69 and the front side of the swinging arm is provided with an opening 70. Extending through these two openings is the valve stem 68 of the cup-shaped valve 47. The clearance between the valve stem 68 and the opening 69 is quite close, but the clearance between the reduced and free end of the valve stem 68 and the opening 70 is quite large so that the face of the cup-shaped valve 47 may be free to adjust itself relative to the flat sliding surface 48 of the upright body bracket 36. A spring 71 is interposed between the cup-shaped valve 47 and the rearward side of the swinging arm 49. This spring 71 resiliently presses the face of the cup-shaped valve 47 against the flat surface 48 of the upright bracket 36.

As illustrated best in Figures 1 and 2, the upright body bracket 36 is provided with a duct 31 that is adapted to be connected in communica-

tion with a hose 41 which is, in turn, connected to the intake manifold of an internal combustion engine. At the top of the duct 31, there is provided a fitting 39 having a restriction 38 into which is threadably attached a nipple 40 over which the hose 41 is connected. The lower end of the duct 31 terminates in an opening 44 in the face 48 of the upright bracket 36. Spaced to the left of the opening 44 is an opening 45 which rearwardly extends through the upright bracket 36 and which is connected in communication with the left hand piston chamber 29 by means of a tube 43 and a fitting 59 having a restriction. See Figure 3. By means of similar construction, there is spaced to the right of the opening 44, an opening 46 which is connected in communication with the right hand piston chamber 30 by means of a tube 42.

A cover 87 may be employed to keep the working parts of the toggle switch and valve assembly 9 free of dirt and other foreign particles. The lower edge of the cover 87 may rest upon a suitable flange provided in the edge of the bracket 15. The upper flat central part of the cover 87 may be provided with an opening 20 through which the fitting 39 may extend and allow the flange of the said fitting 39 to hold the cover 87 against the upper end of the upright bracket 36. The cover 87 may also be provided with slits through which the tubes 42 and 43 may pass when inserting or removing the cover. The entire assembly may be mounted upon, but insulated from, any suitable part of the motor vehicle. To accomplish this mounting, the bracket mounting 88 which is adapted to be connected to the motor vehicle has its upper end connected to a block of insulation 89 by means of screws 91. The insulated block 89 is in turn connected to the upright body bracket 36 by means of the screws 90. The entire assembly is insulated from the motor vehicle for the reason that the common terminal 86 is electrically connected to the bracket 15.

In the operation of my device, let it be assumed that the hose 41 is connected to the intake manifold of an internal combustion engine and that the position of the swinging arm 49 is the same as that shown in Figure 1. In this position, the opening 44 is connected in communication with the opening 45 through means of the cup-shaped valve 47. This means that the left hand piston chamber 29 is connected in communication with the vacuum of the intake manifold of the internal combustion engine and that the right hand piston chamber 30 is connected to atmosphere through the opening 46. Therefore, the piston is urged to the left as shown in Figure 1. As the piston proceeds to the left, the oscillatory offset lever 54 is rotated in a clockwise direction about the fulcrums 56 and 57. This means that the upper end of the oscillatory offset lever 54 swings to the right. As the upper end of the oscillatory offset lever 54 swings to the right beyond a certain point, the spring 58 snaps the swinging arm 49 to the right thereby connecting the opening 46 in communication with the opening 44. Under this condition the right hand piston chamber 30 is connected in communication with the vacuum of the intake manifold of the internal combustion engine and the opening 45 is connected in communication with the atmosphere. Under this condition, the piston is urged to the right, and as it reaches a certain point, the swinging arm 49 swings to the left being in the position shown in Figure 1.

This oscillatory action continues so long as the device is connected in communication with the vacuum of the intake manifold of the internal combustion engine. The rate of the oscillatory motion may be adjusted by using a fitting 39 having the correct size of restriction 38. If the restriction is small the action will be slow, and if large the action will be fast. The action of the swinging arm 49 is quite quick by reason of the snap action of the toggle arrangement. Therefore, when my device is connected in circuit relation with a dual flasher system, the arrangement is such that in the left hand position of the swinging arm 49 such as shown in Figure 1, one set of the dual flasher lights is connected in circuit relation with the terminal 85 and the common terminal 86, and when the swinging arm 49 is in the right hand position, the other set of the flasher lights is connected in circuit relation with the terminal 86 and the common terminal 85.

Inasmuch as my device is connected in communication with the vacuum of the intake manifold of an internal combustion engine, the action of my invention is such that, when the motor vehicle is running normally and on a level road, the frequency at which the dual sets of flasher lights are operated decreases as the speed of the vehicle increases and such that the frequency at which the dual sets of flasher lights are operated increases as the speed of the motor vehicle decreases. This means that when a car is slowing down, the dual set of flasher or warning lights flicker faster than they will when the car is increasing in speed. This gives the maximum degree of warning when it is most needed.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In combination, a cylinder having an opening, a foreshortened piston having two heads mounted in the cylinder, thereby making a piston pressure chamber on opposite ends of the piston, a longitudinal member for connecting the two piston heads together, a toggle actuated switch assembly having a saddle, a quick acting switch arm pivotally mounted on the saddle, and an oscillatory member for actuating the quick acting switch arm, means for mounting the saddle upon the cylinder and having a portion extend inside the cylinder through the said opening, means for actuating the oscillatory member by the said longitudinal member, thereby actuating the quick acting switch arm in accordance with the movements of the piston, a valve for controlling the pressure in the piston chambers, and

means for actuating the valve by the quick acting arm.

2. In combination, a pressure actuated device having a housing and a movable part mounted therein and actuated by the pressure therein, a toggle actuated switch assembly having a saddle, a quick acting switch arm pivotally mounted on the saddle, an oscillatory member for actuating the quick acting switch arm, means for mounting the saddle upon the pressure actuated device and having a portion extend inside the housing, said oscillatory member pivotally engaging the saddle inside of the housing, means for actuating the oscillatory member by the said movable part, thereby actuating the quick acting switch arm in accordance with the movements of the movable part, a valve for controlling the pressure in the pressure actuated device, and means for actuating the valve by the quick acting arm.

3. In combination, a pressure actuated device having a housing and a movable part mounted in said housing and actuated by the pressure therein, fulcrum means supported by the pressure actuated device, a switch having a quick acting switch arm mounted outside of the housing and pivotally engaging the fulcrum means, a second fulcrum means supported by the pressure actuated device, an oscillatory member pivotally engaging the second fulcrum means and extending into said housing, resilient means interconnecting the oscillatory member and the quick acting switch arm, so that movement of the oscillatory member causes the resilient means to actuate the quick acting switch arm, means for actuating the oscillatory member by the said movable part, thereby actuating the quick acting switch arm in accordance with the movements of the said movable part, a valve for controlling the pressure in the pressure actuated device, and means for actuating the valve by the quick acting switch arm.

4. In combination, a pressure actuated device having a housing and a movable part mounted in said housing and actuated by the pressure therein, a fulcrum member mounted on the housing, said fulcrum member having two fulcrum means, a switch having a quick acting switch arm pivotally engaging one of said fulcrum means, an oscillatory member pivotally engaging the other of said fulcrum means, means for actuating the oscillatory member by the said movable part, resilient means interconnecting the oscillatory member and the quick acting switch arm, thereby causing the movements of the oscillatory member and the resilient means to actuate the quick acting switch arm in accordance with the movements of the said movable part, a valve for controlling the pressure in the pressure actuated device, and means for actuating the valve by the quick acting switch arm.

ELMER F. KETTUNEN.
